Eric J. Selldin, North Arlington, N. J.

Application March 22, 1945, Serial No. 118,642

Term of patent 7 years

(Cl. D17—6)

To all whom it may concern:

Be it known that I, Eric J. Selldin, a citizen of the United States of America, residing at North Arlington, in the county of Bergen and State of New Jersey, have invented a new, original, and ornamental Design for a Clothespin, of which the following is a specification, reference being had to the accompanying drawing, forming part thereof.

Figure I is a front elevation of a clothespin showing my new design.

Figure II is an elevational view of one side thereof.

Figure III is a front perspective view of the same.

Figure IV is a top plan view thereof.

I claim:

The ornamental design for a clothespin, substantially as shown.

ERIC J. SELLDIN.
